UNITED STATES PATENT OFFICE.

MARY G. HATCH, OF NEW YORK, ASSIGNOR TO M. H. BIRGE & SONS, OF BUFFALO, NEW YORK.

DESIGN FOR WALL-PAPER.

SPECIFICATION forming part of Design No. 22,942, dated November 28, 1893.

Application filed October 21, 1893. Serial No. 488,821. Term of patent 3½ years.

To all whom it may concern:

Be it known that I, MARY G. HATCH, a citizen of the United States, residing at New York, in the county and State of New York, 5 have invented and produced a new and original Design for Wall-Paper, of which the following is a specification.

The design consists of bunches of flowers tied together by flowing ribbons and arranged 10 in a regular manner over the surface of the paper as represented in the accompanying drawing. The border forming the upper portion of the design is formed of groups of the same flowers tied by flowing ribbons and interlacing ribbons as shown. 15

What I claim is—

The design for wall paper herein shown and described.

Witness my hand this 14th day of October, 1893.

MARY G. HATCH.
